UNITED STATES PATENT OFFICE.

THOMAS B. ATTERBURY, OF PITTSBURG, PENNSYLVANIA.

DESIGN FOR A JAR.

SPECIFICATION forming part of Design No. 18,685, dated October 16, 1888.

Application filed September 20, 1888. Serial No. 85,938. Term of patent 3½ years.

To all whom it may concern:

Be it known that I, THOMAS B. ATTERBURY, a citizen of the United States, residing at Pittsburgh, in the county of Allegheny and State of Pennsylvania, have invented and produced a new and original Design for Jars; and I do declare the following to be a full, clear, and exact description of the same, reference being had to the accompanying drawing, forming a part thereof.

The design is illustrated in the accompanying drawing, in which the jar is shown in front elevation.

The main body A of the jar flares upward and outward from the base A' to the central portion or line, B, and from thence the sides of the jar are gradually contracted to the band or neck portion C, from which point the sides are again swelled to form the portion D, the upper end of the portion D being contracted and screw-threaded.

The main body of jar A is provided with

longitudinal ribs or flutes a, which extend from the base A' to the band C of the neck, and the portion D is also provided with longitudinal ribs or flutes b, which extend from the band C to the top of the jar.

The band C is composed of a series of small circumferential ribs, d, which terminate in a knot or bow, e, the ends e of which extend down over a portion of the body A.

What I claim is—

The design for jars herein described, consisting of the portions A and B, having longitudinal ribs or flutes, and the circumferential band C, with the knot or bow e, substantially as shown and specified.

In testimony whereof I affix my signature in presence of two witnesses.

THOMAS B. ATTERBURY.
